ATTORNEY.

UNITED STATES PATENT OFFICE.

STONE GUNNAR PALMBERG, OF CHICAGO, ILLINOIS.

DESIGN FOR A COMBINATION CUTLERY ARTICLE.

58,817.

Specification for Design.

Patented Aug. 30, 1921.

Application filed April 15, 1921. Serial No. 461,700. Term of patent 7 years.

To all whom it may concern:

Be it known that I, STONE G. PALMBERG, a citizen of the United States, residing at Chicago, in the county of Cook and State of Illinois, have invented a new, original, and ornamental Design for a Combination Cutlery Article, of which the following is a specification, reference being had to the accompanying drawing, forming part thereof.

Figure 1 is a plan view of the device, and Fig. 2 is an edge view thereof.

I claim:

The ornamental design for a combination cutlery article as shown.

STONE GUNNAR PALMBERG.
